THOMAS DRAKE, OF CINCINNATI, OHIO.

Design No. 4,790, dated April 11, 1871.

DESIGN FOR A HINGE.

The Schedule referred to in these Letters Patent and making part of the same.

I, THOMAS DRAKE, of Cincinnati, in the county of Hamilton and State of Ohio, have invented and produced a new and original Design for a "Door-Hinge," of which the following is a specification.

Description of the Accompanying Drawings.

Figure 1 is a perspective view of a door-hinge embodying my design;

Figure 2 is a plan of the same in its open position; and

Figure 3 is a horizontal section, showing the hinge closed.

The nature of my design consists in a new and ornamental configuration for the class of hinges which has a leaf with an arm projecting at right angles, so as to embrace the door upon both its face and its

edge, and is fully represented in the accompanying drawings, to which reference is made.

I am aware that hinges have been made whose leaf has consisted of two parts at right angles to each other, so as to embrace both the face and the edge of the door, and therefore make no claim to such; but

I claim as new and desire to secure by Letters Patent—

The design for the ornamental configuration of hinge, substantially as represented.

In testimony of which invention I hereunto set my hand.

THOMAS DRAKE.
